Primary Examiner—Ted Shooman*Assistant Examiner*—C Tuttle*Attorney, Agent, or Firm*—William E. Hein**[57]****CLAIM**

The ornamental design for a tool for precision haircutting, as shown and described.

DESCRIPTION

FIG. 1 is a front perspective view of a tool for precision haircutting, showing my new design;

FIG. 2 is a front elevation view, the rear elevation view being a mirror image thereof;

FIG. 3 is a top plan view;

FIG. 4 is left side elevation view; and,

FIG. 5 is a right side elevation view.

The surface(s) or portion(s) of the article not shown in the drawing or described in the specification form(s) no part of the claimed design.
